UNITED STATES PATENT OFFICE.

LEO POTTER, OF NEW YORK, N. Y.

DESIGN FOR A HAND-BAG.

Patented Mar. 26, 1912.

42,370.

Specification for Design. Application filed August 11, 1911. Serial No. 643,629. Term of patent 3½ years.

To all whom it may concern:

Be it known that I, LEO POTTER, a citizen of the United States, residing at New York, borough of Manhattan, county and State of New York, have invented a new, original, and ornamental Design for Hand-Bags, of which the following is a specification.

My design is illustrated in the accompanying drawing forming a part of this specification, in which—

I claim:

The ornamental design for a hand-bag as shown.

LEO POTTER.

Witnesses:

LOUIS M. COHEN,
JOHN J. CLARK.
